Primary Examiner — Philip S Hyder(57) **CLAIM**

The ornamental design for a screwdriver, as shown and described.

DESCRIPTION

This patent application may be related to one or more of the following patents granted to the inventor herein: U.S. Pat. Nos. 5,592,862 and D373,061.

FIG. 1 is front elevation view thereof;

FIG. 2 is a rear elevation view thereof;

FIG. 3 is a right-side elevation view thereof;

FIG. 4 is a left side elevation view thereof;

FIG. 5 is a top plan view thereof; and,

FIG. 6 is a bottom plan view thereof.

The broken line disclosure shown in FIGS. 1, 2, 3, 4, 5 and 6 define the boundaries of the claimed subject matter but form no part of it.
